US00D721371S

(12) **United States Design Patent**
Rivera et al.

(10) **Patent No.:** **US D721,371 S**
(45) **Date of Patent:** **** Jan. 20, 2015**

(54) **CODE SCANNER**

(71) Applicants: **Steve S. Rivera**, Brookline, MA (US);
John M. Jannetty, Quincy, MA (US);
Jonathan M. Fisher, Somerville, MA (US); **Harald Prokop**, Cambridge, MA (US)

(72) Inventors: **Steve S. Rivera**, Brookline, MA (US);
John M. Jannetty, Quincy, MA (US);
Jonathan M. Fisher, Somerville, MA (US); **Harald Prokop**, Cambridge, MA (US)

(73) Assignee: **SCVNGR, Inc.**, Boston, MA (US)

(**) Term: **14 Years**

(21) Appl. No.: **29/449,235**

(22) Filed: **Mar. 14, 2013**

(51) **LOC (10) Cl.** **14-02**

(52) **U.S. Cl.**

USPC **D14/420**

(58) **Field of Classification Search**

Primary Examiner — Susan Moon Lee

(74) *Attorney, Agent, or Firm* — Morgan, Lewis & Bockius LLP

(57) **CLAIM**

The ornamental design for a code scanner, substantially as shown.

DESCRIPTION

FIG. 1 is a perspective view of a code scanner incorporating the design;

FIG. 2 is a front view thereof;

FIG. 3 is a back view thereof;

FIG. 4 is a left-side view thereof, the right-side view being a mirror image of the left-side view;

FIG. 5 is a bottom view thereof; and,

FIG. 6 is a top view thereof.

1 Claim, 4 Drawing Sheets
